DESIGN FOR A CONCRETE MIXER

Charles F. Ball, Franklin, Pa., and Louis G. Hilkemeier, Milwaukee, Wis., assignors to Chain Belt Company, Milwaukee, Wis., a corporation of Wisconsin

Application December 8, 1941, Serial No. 104,542

Term of patent 14 years

To all whom it may concern:

Be it known that we, Charles F. Ball and Louis G. Hilkemeier, each a citizen of the United States and residing respectively at Franklin, in the county of Venango and State of Pennsylvania, and at Milwaukee in the county of Milwaukee and State of Wisconsin, have invented a new, original, and ornamental Design for a Concrete Mixer, of which the following is a specification, reference being had to the accompanying drawings, forming a part thereof.

In the said drawings:

Figure 1 is an elevational view of the concrete mixer, as seen from the left hand side thereof;

Figure 2 is a top plan view of the same;

Figure 3 is an elevational view, as seen from the right hand side of the mixer; and

Figure 4 is an elevational view, as seen from the rear thereof.

We claim:

The ornamental design for a concrete mixer, as shown.

CHARLES F. BALL.
LOUIS G. HILKEMEIER.
